SUPPORTING HOLDER FOR CONTAINER
BLANKS

André Schick, Lausanne, Switzerland

Application August 2, 1950, Serial No. 177,257
In France March 10, 1950

6 Claims. (CL. 93—49)

1.

This invention relates to a special holder or support for container blanks which enables a salesperson to form the blank progressively into box-like form at the time the sale is made.

The handling of container cardboard blanks used for packing choice foodstuffs, more particularly articles of pastry, requires a great deal of dexterity on the part of the sales lady who has to hold the partially formed box in equilibrium, keep it from getting soiled while the buyer makes his choice, fold the flaps of the sheet of cardboard, and hook the flaps together after the container is completed. True, there exist means intended to fold the edges of the cut-out sheets of cardboard. There is, for instance, a device or form resembling a food plate into which the pre-cut cardboard blank is previously inserted for the purpose of raising the four corners and thus to give the cardboard the shape of a packing box. This procedure has the disadvantage, however, that the cardboard must subsequently be removed from the form be independently manipulated by hand as a separate operation in order to fill the box with merchandise and close it. Moreover, this method of getting the box ready requires a different plate for every size; in other words, there will be as many plates as there are packing sizes. This takes up space.

To eliminate the foregoing objections, the present invention has for its object a supporting holder designed to assist in folding container blanks made from cut-out sheets of cardboard. This device may be used to fold, depending on requirements in each instance, either a single size of cardboard box blank or several different sizes with the same device and to support the blank during the various stages of its manipulation, i. e., while it is being filled with merchandise and subsequently closed.

The accompanying drawing shows, diagrammatically and by way of example, two forms of execution of the device incorporating the features of the invention.

In the drawing:

Fig. 1 is a front elevation of one embodiment of a supporting holder for a given size.

Fig. 2 is a top view thereof.

Fig. 3 is a side elevation of the holder shown in Fig. 1.

Fig. 4 is a sectional view taken on line IV—IV of Fig. 2.

Fig. 5 is a top view, on a reduced scale, of a blank in the form of a spread-out sheet of cardboard with cut-out portions and fold lines, such as must be fashioned in order to be usable with the supporting holder shown in Figs. 1—4.

2.

Figs. 6—8 are views showing various intermediate stages of folding the sheet of cardboard of Fig. 5 by means of the supporting holder with a view to finally obtaining the ultimate configuration of the container represented in Fig. 8.

Fig. 9 is a side elevation of a second embodiment for a supporting holder making it possible to obtain containers of several sizes.

Fig. 10 is a plan view of Fig. 9 showing in dot-dash lines an intermediate position of the extensible members.

Fig. 11 is a vertical section along line XI—XI of Fig. 10.

Fig. 12 is a fragmentary view of Fig. 10 showing the structure of the handle from the inner side, between the two bottom halves, and

Fig. 13 is a horizontal view, from below, of a fragment of Fig. 10.

Similar reference characters designate corresponding parts throughout the drawings.

According to the first form of the invention shown in Figs. 1—4 the supporting holder is in one piece and in both forms resembles a fork, or scoop. For example, the device is made in a single piece of light-weight metal by stamping and folding and is subsequently plated with chromium or nickel to render it rustproof. It could also be molded in synthetic material.

The essential parts of the supporting holder shown in the drawings consist in a bottom wall 1, with the center part cut away so as to provide two lateral arms 2 and 3, and its rear part bent upward to form a vertical wall 4, the upper end 5 of which is then rounded backward and downward to provide a handle to hold the supporting holder once the sheet of cardboard has been engaged therein.

From either side of the vertical back wall 4 extends the arms or blank hold-down strips 6 and 7, respectively, bent at right angles forwardly to terminate in a tapering end in the shape of a hook 8. These strips 6 and 7 are flanked on the outside by side wall forming flanges 9 and 10, respectively, slightly curved inwardly and formed at the lateral edges of bottom 1 which are turned up vertically to constitute, together with strips 6 and 7, guiding slots for one of the embryo side walls of the blank, as will hereinafter be described more in detail. The forward ends 11 of these flanges in the shape of a pointed spoon are separated from arms 2 and 3, respectively, by a slot 12 to permit the engagement of the adjacent side walls of the sheet of cardboard in the supporting holder, these side walls being thus guided by said spoon portions 11 into vertical position.

A sheet or blank of cut-out cardboard 13, to be formed and folded by the supporting holder above described, is shown in Fig. 5 in its spread-out state. The rectangular bottom of this sheet comprises a fold line, indicated in the drawing by a rectangular broken line 14. This fold line is outwardly surrounded by an oblong rectangle 15, concentric and parallel with fold line 14, and also shown in the drawing by another broken line. By inserting the sheet of cardboard into the supporting holder, it is creased or folded along three sides of the broken line 14, namely, the back and two sides, thereby first forming three vertical walls 18 around what then becomes the final rectangular bottom wall. By continuing the folding along the other or front broken line 14 and then folding all four side walls on the outer broken line 15, four tabs 16 and four flaps 17 are formed. The box is closed by folding the flaps a third time. Tabs 16 are separated from the opposite vertical walls 18' and 18'' by slots having at their inner end a recess 19 for the purpose of engaging hooks 8 of the supporting holder in the cardboard so as to produce the container. Finally, the ends of flaps 17 are provided with slots 19' to form closing hooks, making it possible mutually to engage opposite flaps so as to close the container for transportation.

The successive stages of folding the cardboard container blank shown in Fig. 5 and described above are carried out with the aid of the supporting holder, as will be seen from Figs. 6 to 8. The first stage, Fig. 6, shows how the supporting holder engages by means of its hooks 8, the recesses 19 of the blank. By pushing the supporting holder all the way in the direction of arrow f, the lateral walls 18, 18', and 18'' located between fold lines 14 and 15, are automatically raised around bottom wall 13 under the action of the spoon portions 11 of flanges 9 and 10, so that the sheet of cardboard assumes the shape of a box closed on three sides. The fourth side remains open, that is, in the plane of bottom wall 13. Consequently the merchandise can now be introduced horizontally from that side, while one holds the container, retained by the supporting holder, conveniently with the other hand, as shown in Fig. 7. The fourth wall 18''' is then folded, and tabs 16 are introduced into the interior of the container. Finally, the salesperson mutually engages hooks 19' of each pair of opposite flaps 17 so as to ensure the perfect closing of the container, as shown in Fig. 8.

The supporting holder of the type above described permits only of folding cardboard blanks of which one of the bottom dimensions 13 (Fig. 5) remains constant. In fact, that dimension must correspond to the spacing between flanges 9 and 10; in other words, the distance between recesses 19 of the slots separating flaps 17 and tabs 16 cannot vary for a given supporting holder. This means that in practice the same supporting holder can be used only for blanks whose bottom may vary in a single dimension—lengthwise, for example, whereas the width must conform to the distance between lateral strips 6 and 7 of the supporting holder. If containers with different width are desired, it will be necessary to use in each instance a different supporting holder, i.e. one corresponding to the distance between strips 6 and 7.

The form of embodiment shown in Figs. 9-13 remedies the aforementioned disadvantages, since it relates to a supporting holder with extensible flanges. In these figures the device comprises a

bottom consisting of two halves 21, 22, thus forming two lateral arms 21' and 22', respectively. These two halves are secured to a crosspiece serving the purpose of a handle and comprising three sections, namely, a middle section 23 and two movable lateral blocks or sections 24 and 25, located on either side of the middle section. The three sections are aligned end to end so as to form an extensible cross member. They are assembled by means of a sheath 26, secured at 27 to the middle section 23.

Sections 24 and 25, which can be displaced in sheath 26, are mutually connected by a guide strip 28, embedded or countersunk under the said sections. Strip 28 is provided with slots 29 in which fixing screws 30 or the movable sections 24 and 25 can slide. On the other hand, sheath 26, in turn, is provided with slots 31, in which headed screws 32 can slide, thus securing the movable sections 24 and 25 to the sheath.

The lateral sides of arms 21' and 22' are fashioned in the same manner as those of the first form of execution previously described. The lateral edges of the two halves 21 and 22, which constitute the bottom, as well as arms 21' and 22' are bent at right angles upward to form at either side flanges 33 and 34, respectively, slightly arched at their free ends to resemble a spoon. Adjacent to each flange and within the outline of the supporting holder is a strip 35, of the same length and extending in the same direction as the flanges, with its free end tapered and slightly twisted so as to raise, in cooperation with the arched part of the flanges, the sides of the blank which has to be transformed into a container or packing box. These strips are secured each to one of the movable sections 24 and 25, respectively.

As pointed out above, the supporting holder just described is extensible, since arms 21' and 22' can be moved relative to each other in such a way as to render the holder adaptable to different sizes of cut-out sheets of cardboard. An intermediate position of adjustment is represented in dot-dash lines in Fig. 10, showing at 33' and 34' the position of flanges 33 and 34 and, at 35', the adjusted position of hook 35. In this intermediate position, sections 24 and 25 of the handle are shown displaced to 24' and 25', respectively.

When a container is to be made from a sheet of cardboard cut out to certain dimensions, the sections 24 and 25 of the extensible supporting holder are manually adjusted in such a way as to make the ends of strips 35 correspond with the distance between recesses 19 (Fig. 5) provided at the base of the slots separating tabs 16 from the closing flaps of the sheet of cardboard. This adjustment is accomplished by spacing the movable sections as required so that the outline of the supporting holder will correspond to the distance between recesses 19 located on the same side of the adjacent flap. The free ends of strips 35 are then introduced into the recesses of the sheet of cardboard, by holding with one hand the supporting holder and with the other hand holding the blank and then pushing the latter slightly, so as to cause the strips to enter the recesses. The arched configuration of flanges 33, 34, which cooperate with the strips 35, results in the two sides of the blank engaged in the supporting holder being raised, whereas the third side is raised by encountering the resistance of the back wall having the handle. We now have three vertical walls for the container. The fourth side opposite the one engaged between flanges 33 and

34 is left flat so as to permit introduction of the merchandise to be packed into the container.

After the container has been filled, it is closed by fitting together the hooks of the flaps raised by the flanges, whereupon the supporting holder is withdrawn so as to disengage the container which thus assumes the shape of a box with quadrangular base and with an arched top.

From the foregoing, it will be seen that this extensible or adjustable form of the invention makes it possible to prepare, with the same supporting holder, a greater variety of containers by using different size blanks with varying spacing of the slots.

I claim:

1. A supporting holder for container blanks, comprising, a bottom wall, a back wall, a handle on the back wall, blank hold-down strips extending forwardly from the back wall, and side wall forming flanges carried by opposite sides of the bottom wall, said flanges being turned upwardly and spaced outwardly from the strips to provide a guideway for receiving the side wall portions of a blank and turning them upwardly while the bottom portion of the blank is held against the bottom wall by said strips.

2. A supporting holder according to claim 1, wherein, the bottom wall is in the form of a fork.

3. A supporting holder according to claim 1, wherein, the handle is formed integrally with said back wall.

4. A supporting holder according to claim 1, wherein, said strips are tapered toward their front ends and formed with hooks for engaging a portion of the blank.

5. A supporting holder according to claim 1, wherein, the flanges are of arcuate formation

vertically and also tapering forwardly after the fashion of a spoon, and the tips of the flanges are notched inwardly at their forward ends relative to the related portion of the bottom wall.

5. A supporting holder for container blanks, comprising, a bottom wall including separable sections, a handle unit adjustably connecting said sections, said unit including a pair of aligned blocks secured at their forward ends to a related bottom wall section and each having a downwardly opening recess, a sheath underlying the front, top and back portions of the blocks to span the joints therebetween, means for securing the sheath to the front face of the blocks, a guide strip in said recess and having slots, guide pins on the blocks and riding in the slots whereby the blocks are slideable relative to each other beneath the sheath, blank hold-down strips extending forwardly from the blocks, side wall forming flanges spaced outwardly from the strips and also carried by the blocks, said flanges forming guideways with the strips for receiving the side wall portions of a blank and turning them upwardly while the bottom portion of the blank is held against the bottom wall by said strips.
